(57) **CLAIM**

The ornamental design for an electrical connector as shown and described.

DESCRIPTION

FIG. 1 is a front view of an electrical connector showing our new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a front perspective view thereof;

FIG. 8 is a rear perspective view thereof;

FIG. 9 is a cross-sectional view taken along the line 9-9 in FIG. 1; and,

FIG. 10 is a cross-sectional view taken along the line 10-10 in FIG. 1.

The dot-dot broken lines in the drawings illustrate portions of the electrical connector that form no part of the claimed design. The dot-dash broken lines in the drawings depict the boundaries of the claimed subject matter, and thus form no part of the claimed design.
